DRYING APPARATUS AND METHOD OF
DRYING

Glen Overton, Dowagiac, Mich.

Application February 4, 1939, Serial No. 254,662

7 Claims. (Cl. 34—39)

This invention relates to drying apparatus and more particularly to a unit of drum driers for dehydrating liquid or pasty material in film form.

In accordance with the principles of this invention, a pair of main drum driers are arranged in adjustable surface spaced relation with their axes substantially horizontal and auxiliary rolls which may be smaller than the main drum driers are associated with the upper portions of the main drums to serve in the distribution of the material to be dried over the surfaces of the main drums and also as auxiliary driers. Means are provided for independently heating the main and auxiliary drums so as to maintain temperature differentials therebetween, if desired, for facilitating the adherence of the material to be dried to the main drum surfaces rather than to the surfaces of the auxiliary rolls.

In order to facilitate further the formation of continuous, uniform films on the main drum driers, means are provided for driving the auxiliary rolls in the same surface direction as the main drums at the nips formed with the main drums but at a different and preferably a slower surface speed than that of the main drums. The rubbing action thus produced at the nips causes the films of material to be dried to adhere better to the faster rotating surfaces of the main drums and to spread out more uniformly.

Scraping means are provided in connection with each of the main drums to remove the film of dried material therefrom. Means also are provided to form, in cooperation with the auxiliary rolls, pockets on the upper surfaces of the main drums into which the material to be dried can be fed. This novel arrangement of drying apparatus facilitates the drying of relatively non-adherent liquid and pasty material and greatly increases the drying capacity over that of other types of individual drum driers heretofore used.

It is therefore an important object of this invention to provide an improved construction of drum drying apparatus for use in the drying of liquids and pasty materials that do not readily form adherent films on drying surfaces.

It is a further important object of this invention to provide a unit drier comprising a pair of main drier drums adjustable relative to each other to control the characteristics of the film of material being dried, and a pair of auxiliary rolls provided with independent heating means and with means for driving the rolls at a different surface speed from the drums, the rolls also being adjustable with respect to the surfaces of the main drums to serve in spreading the material

to be dried into film form on the surfaces of the main drums and also to aid in the drying of the material.

Other and further important objects of this invention will be apparent from the disclosures in the specification and the accompanying drawings.

This invention (in a preferred form) is illustrated in the drawings and hereinafter more fully described.

On the drawings:

Figure 1 is an end elevational view of a drying apparatus embodying the principles of my invention;

Figure 2 is a top plan view;

Figure 3 is a view of a longitudinal section along the line III—III in Figure 1, with parts in elevation;

Figure 4 is a view of a transverse section along the line IV—IV in Figure 2.

As shown on the drawings:

The reference numeral 10 indicates generally a pair of end housings provided with a pair of openings 11 and 12 through which extend the journals 13 and 14 of a pair of main drier drums 15 and 16, respectively. Said journals 13 and 14 are supported in bearing housings 17 and 18, respectively, mounted adjustably upon guideways 19 and 20, respectively. Adjusting screws 21 and 22 provide for individual adjustment of each bearing housing 17 in the guideways 19, and similar adjusting screws 23 and 24 associated with each end bearing housing 18 permit adjustment thereof to vary the spacing between the surfaces of said main drier drums 15 and 16, as indicated at 25. Said drums 15 and 16 are thus arranged with their axes in substantially the same horizontal plane and with their peripheries relatively adjustable with respect to each other.

An auxiliary roll 26 is mounted above the main drier drum 15 with its ends journaled in a pair of bearing housings 27 supported from the end frames 10 in guideways 28. Adjusting screws 29 and 30 associated with each of the guideways 28 permit adjustment of the roll 26. A similar auxiliary roll 31 is mounted above the drier drum 16 with its end journaled in bearing housings 32 supported in guideways 33 upon the end frames 10. Adjusting bolts 34 and 35 permit relative adjustment of the roll 31 with respect to the drier drum 16.

The drums 15 and 16 and the rolls 26 and 31 are provided with projecting shoulders 45, 46, 74 and 75 respectively.

The driving means for the drums 15 and 16 and the rolls 26 and 31 may suitably comprise a driving shaft 65. A geared wheel 66 is mounted on the driving shaft 65 and engages the geared wheel 67 mounted on the shaft of the drum 15. The drum 16 is similarly driven by means of a suitably mounted geared wheel 68 engaging both the geared wheel 66 and the geared wheel 69 mounted on the shaft of the drum 16.

For driving the rolls 26 and 31 suitably mounted geared wheels 70 and 71 are provided which engage, respectively, the geared wheels 66 and 68. Geared wheels 72 and 73 are mounted, respectively, on the shafts of the rolls 26 and 31. The geared wheels 70 and 72 engage each other, as do 15 the geared wheels 71 and 73.

The ratio of the diameters of these geared wheels is so chosen that the rolls 26 and 31 are rotated at a slower surface speed than the drums 15 and 16. Preferably the surface speed 20 of the drums 15 and 16 is from 10% to 40% greater than that of the rolls 26 and 31. The direction of rotation of the surfaces of the drums 15 and 16 at the point indicated by 25 is downward.

A scraping member, blade or the like 36 is associated with the main drier drum 15 for removing the film of dried material formed thereon, indicated by the reference numeral 37. Said scraper member 36 is secured upon a rod 39, 30 which is pivotally mounted at its ends in bosses 40 formed on the end frames 10. Adjusting mechanism for said scraper 36 comprises a pair of stationary brackets 41 and adjusting bolts 42 threaded therethrough into a pair of brackets 35 38, which are secured to the rod 39. By adjustment of said bolts 42, the scraping member 36 is held under the desired pressure against the surface of the drum 15. A similar adjustable scraping mechanism, indicated generally by the reference numeral 43, is associated with the drier drum 16 for removing a film 44 of dried material from said drum.

A wooden board 95 is suitably mounted on the brackets 38 facing the roll 26. It conforms 45 to and is held lightly against the surface of the drum 15 but extends past the ends of said drum to the outside of the end housings 10. Upwardly the board 95 extends as high as the brackets 38. A similar board 96 is mounted in 50 like manner facing the roll 31.

A wooden board 76 is positioned perpendicularly to the drums 15 and 16 and the rolls 26 and 31 at one end thereof and another board 77 at the other end thereof. The shape of the wooden boards is such as to conform to the projecting shoulders 45, 46, 74 and 75. The wooden boards 76 and 77 reach upwardly to a line going through the center of the rolls 26 and 31; downwardly to a line going through the center of the drums 15 and 16 and in the other directions so as to contact the boards 95 and 96. The wooden boards 76 and 77 are held lightly against the ends of the drums 15 and 16 and the rolls 26 and 31 by springs such as 78 and 79 mounted upon pins such as 80, 81, 82 and 83 which project from the sides of the boards away from the drums and rolls into suitable apertures in the end housing 10.

Pockets 47 and 48 respectively, are formed between the respective rolls 26 and 31, boards 95 and 96 and boards 76 and 77. The material to be dried is fed into said pockets 47 and 48 to form accumulations indicated by the reference numerals 49 and 50, respectively, from which, 70 75

in the operation of the machine, the material is spread over the surfaces of the drums 15 and 16 in films of uniform thickness.

A trough 51 is secured to the end frames 10 in a position adjacent to the lower portion of the drier drum 15 for receiving the dried material 37 as it is scraped from the surface of the drum. Said trough 51 may be provided with a screw conveyor 52 for discharging the contents of the trough at one end thereof. A similar trough 53 and screw conveyor 54 is provided in association with the drier drum 16.

The drier drums 15 and 16 are provided with valve controlled steam pipes 55 and 56, respectively, and the auxiliary rolls 26 and 31 are provided with valve controlled steam pipes 57 and 58, respectively, by means of which said drums and rolls can be internally heated to the desired temperatures independently of each other.

A bar 84 slidably mounted in bearings 85 and 86 in the end housings 10 extends above and parallel to the pocket 47 at the level of the top of and a slight distance in front of the roll 26. The bar 84 is so long that approximately $\frac{1}{6}$ of its length projects outside the bearings 85 and 86. A similar bar 87 is mounted in like manner in bearings 88 and 89 in front of the roll 31. A cross bar 90 connects the bars 84 and 87. The bars 84 and 87 may be moved backward and forward for a distance not exceeding about $\frac{1}{6}$ of their length by the reciprocating piston 91 connected with the cross bar 90. The piston 91 is activated by steam in the cylinder 92 supported from the housing 10 by the bracket 93. A plurality of rods 94 extend downwardly from the bars 84 and 87; they are bent so as to almost conform to the lower half of the surface of the rolls 26 and 31 and are so long that they extend almost into the nips between the drums 15 and 16 and the rolls 26 and 31. The rods 94 are so spaced on the bars 84 and 87 that the back and forward movement of the latter will never carry any of the bars 94 beyond the ends of the drums 15 and 16.

It will be understood, however, that many details of the drying apparatus described as an example may be changed without departing from the principles of this invention. The driers 15 and 16 and the rolls 26 and 31 may, for instance, equally well be driven by a system of sprocket wheels and chains. The drums 15 and 16 and the rolls 26 and 31 may be heated directly by gas or oil flames. The bars 84 and 87 may be caused to move back and forward by a spring at one end and a wheel rotating around a non-central point actuating the other end. By a rearrangement of the scraping devices and the feeding of the material to be dried into the nip 25 between the main drier drums 15 and 16 60 the direction of rotation of said drums and rolls may be reversed from that shown. It is also possible to use different arrangements and different numbers of drums and rolls.

In operation, the drums 15 and 16 may be supplied with live steam at say 100 lbs. per sq. in. and the auxiliary rolls 26 and 31 with steam at say 60 lbs. per sq. in. This gives a temperature differential between the surfaces of the drums and that of the heated rolls that tends to cause the material to be dried to adhere to the drum surfaces rather than to the roll surfaces. Under some circumstances, however, the rolls 26 and 31 may be run cold. The speed of rotation of the drums and rolls will, of course, depend upon the drying properties of the mate-

rial and the thicknesses of the film produced on these rolls, as well as the amount of water to be evaporated.

The material to be dried is fed into the pockets 47 and 48 to provide a constant supply of material at these points, as indicated by the reference numerals 49 and 50. The rods 94 moving back and forward through the accumulations 49 and 50 facilitate the escape of any bubbles of steam which may form in said accumulations and which might otherwise cause an unequal distribution on the surface of the drums 15 and 16 of material from said accumulations as the drums 15 and 16 revolve, in spite of the film forming action of the auxiliary rolls 26 and 31. The differential surface speed between the rolls and drums facilitates the adherence of the material to the drum surfaces in uniform contour. Some part of the material to be dried may, however, adhere to the surface of the rolls 26 and 31. Such material will be returned to the accumulations 49 and 50 and ultimately becomes a part of the films that are dried on the surfaces of the drums 15 and 16.

The spacing at the nip 25 between the surfaces of said drums 15 and 16 is so adjusted, as by means of the various adjusting bolts 21, 22, 23 and 24, that the films 60 and 61 adhering to the surfaces of the drums 15 and 16, respectively, are of the desired thickness and compactness. Said films 60 and 61 are dried during the continued rotation of said drums 15 and 16 and are scraped off of said drums by the scrapers 36 and 43 to fall into the troughs 51 and 53, respectively.

Some of the advantages of the drying apparatus just described are that the auxiliary rolls aid in drying the material as well as in the formation of adherent films on the surfaces of the drier drums, thus increasing the drying capacity of the unit. By feeding the material to be dried at the points indicated on the top portions of the drums 15 and 16 and then rotating the drums inwardly toward each other, the material becomes filmed and packed earlier than is the case when the film is regulated and packed only by the same drier drums at the nip 25. This is particularly advantageous in the case of liquid and pasty materials that are not particularly coherent and that do not adhere well to heated drying surfaces. By providing for relative adjustment between the drier drums themselves and between the auxiliary rolls and the drying drums, and by providing for driving the rolls at different surface speeds from the drums and for the independent control of the temperatures of the drums and rolls, the desired uniformity and characteristics of the films of material formed on the surface of the drier drums can be more readily controlled than in other types of apparatus.

The above mentioned advantages adapt my drying apparatus particularly for drying sewage disposal plant sludge, milk, various vegetable and fruit juices and pulps and the like. The superior functioning of my drying apparatus makes possible the production of novel products from starting materials of this type. As an example of how, by a proper adjustment of the drying conditions by means of my drying apparatus, a novel product may be obtained the production of a new type of dried citrus food product will be described.

The starting material comprises the waste from the manufacture of canned fruit juices and fruit sections, more particularly, grapefruit.

This waste includes the rind, cellular tissues and seeds of the grapefruit. In its form as discharged from fruit juice extraction plants it is not suitable for animal consumption except for a very short time, but can be preserved by the method now to be described.

According to my method, the citrus fruit waste, including seeds and all, is first ground up into a pulp or paste in a suitable type of grinding mill. If desired, the seeds can be separated from the waste and dried separately. For this purpose, a hammer mill has been found most satisfactory. The waste is processed until it forms a paste that will flow and is capable of being pumped. As it leaves the mill the paste usually has a moisture content of about 85%.

This paste is fed by suitable means into the pockets 47 and 48. Steam of a pressure between 70 to 100 lbs. per sq. in. is admitted into the drums 15 and 16 which have glass finished surfaces. The drums 15 and 16 and the rolls 26 and 31, which latter may or may not be heated, are adjusted so that the film being dried is less than $\frac{1}{64}$ inch thick. The surface speed of the driers 15 and 16 is adjusted to give a drying time of the film not exceeding 12 seconds, preferably between 5 and 10 seconds. The coherent dried film scraped off the drums 15 and 16 is disintegrated by the conveyors 52 and 54.

Seven to seven and one-half tons of waste are required for the production of one ton of dry product having a moisture content less than 10% and preferably between 6 and 8%. It forms uniform, small flakes of a thickness of not more than a few thousandths of an inch which are suitable for use as a cattle feed. This bran-like product may be used dry or it may be made up into a mush with water, which it readily absorbs.

This process represents a notable advance in the art, since pastes prepared from citrus food products do not wet steel readily and hence are very difficult to spread evenly on a steel drum. It further differs from the processes known to the prior art in that no water has been removed by pressing or other mechanical means so that the final product contains all the solids dissolved or suspended in the water. This explains why I require only seven and one-half tons of waste to produce 1 ton of finished material while other processes require 10 to 11 tons.

I claim as my invention:

1. Drying apparatus comprising a pair of horizontally aligned main drying drums defining a nip therebetween, a spreader roll associated with each drying drum above the nip thereof to spread material over the drum surfaces, means for rotating the drums to move their materials receiving surfaces through the nip in a downward direction, means for adjusting the drums horizontally to control the width of the nip therebetween and means to adjust the spreader rolls relative to their drying drums to gauge the thickness of materials spread on the drums whereby films of material of controlled thickness are adapted to be deposited on the drums by the spreader rolls and compressed in the nips between the drums under controlled pressure.

2. Drying apparatus comprising a pair of horizontally aligned main drying drums defining a nip therebetween, a spreader roll associated with each drying drum above the nip to spread material over the drum surfaces, means for rotating the drums to move their materials receiving surfaces through the nip in a downward direction, means for rotating the spreader rolls to move

material onto the drying drum surfaces in thin film form for passage through the nip between the drying drums, means for heating said drying drums, means for heating said spreader rolls, and control devices for each of said heating 5 means to maintain the drier drums at higher temperatures than the spreader rolls.

3. Drying apparatus comprising a heated drying drum, a spreader roll in adjustable relation thereto to form a nip into which material to be dried may be fed, and means for driving said drum and roll in the same surface direction at the nip but with the roll rotating at a slower surface speed to facilitate spreading said material into a continuous uniform film on said drum. 10

4. The method of drying materials, which comprises feeding the material into the nip between two revolving cylindrical surfaces, rotating said surfaces at different speeds to produce a rubbing and spreading action causing said material to 15 adhere as a film to one of said surfaces and heating said one surface to dry the film thereon.

5. Drying apparatus comprising a pair of heated main drums arranged in adjustable spaced relation with their axes in substantially the same horizontal plane, an auxiliary smaller diameter roll associated with each of said drums, means for adjusting the distance between the surfaces of each drum and its associated auxiliary roll to control the spreading and thickness 20 of the film of material to be dried passing therebetween, means for removing the films of dried material from said drums, means defining in cooperation with said spreader rolls and with the upper peripheries of said drums pockets in which the material to be dried is received, pluralities of rods extending almost into, respectively, each 25 nip between said drums and rolls, and means for

imparting a limited sideway motion to said rods whereby the escape of bubbles from material in the vicinity of said nips is facilitated.

6. Drying apparatus comprising a plurality of main drying drums arranged in adjustable surface spaced relation, smaller diameter rolls mounted above said drums and forming nips therewith, means for adjusting the distance between the surfaces of each drum and its auxiliary roll to control the spreading thickness of the film material to be dried passing therebetween means for removing the films of dried material from said drums mounted in spaced relation about the upper peripheries of said drums, means cooperating with said rolls to define pockets above the upper peripheries of said drums into which the material to be dried is received, means for agitating said material in said nips, means for heating said drums above the boiling point of water and means for driving said rolls in the same surface direction at said nip as said drums but at a slower speed than said drums to cause the spreading of said material as continuous films of uniform thickness on the surfaces of said drums. 15

7. The method of drying materials which comprises feeding said material into the nip between two revolving cylindrical surfaces in such a manner as to form there an accumulation of said material, continuously agitating said accumulation in such a manner as to remove bubbles from the vicinity of said nips while rotating said surfaces at different speeds to produce a rubbing and spreading action causing said material to adhere as a film to one of said surfaces and heating said one surface to a temperature above the boiling point of water to dry the film thereon. 20

GLEN OVERTON.
